UNITED STATES PATENT OFFICE.

CHARLES REINHARDT AND HEINRICH LEBHERZ, OF BROOKLYN, N. Y.

HAIR-CLIPPER.

SPECIFICATION forming part of Letters Patent No. 339,811, dated April 13, 1886.

Application filed August 6, 1885. Serial No. 173,716. (Model.)

To all whom it may concern:

Be it known that we, CHARLES REINHARDT and HEINRICH LEBHERZ, of Brooklyn, in the county of Kings and State of New York, have 5 invented certain new and useful Improvements in Hair-Clippers, of which the following is a specification.

This invention relates to improvements in hair-clippers of that class which are used for 10 clipping the hair close to the scalp or skin, the object of this invention being to adapt the handles of the hair-clipper to different sizes of hands, and supporting the comb-plate at different distances from the scalp, so as to 15 cut the hair either close to the skin or at different lengths.

The invention consists in the construction and combination of parts and details, as will be fully described and set forth hereinafter, 20 and finally pointed out in the claims.

In the accompanying drawings, Figure 1 represents a plan of our improved hair-clipper for barbers' use. Fig. 2 is a side elevation of the same; Fig. 3, a top view with the 25 cap-plate removed; Fig. 4, a vertical longitudinal section on line $x-x$, Fig. 1; Fig. 5, a top view of a modified form of the operating mechanism; Fig. 6, a vertical transverse section on line $y-y$, Fig. 3; Fig. 7, a vertical longitudinal section on line $z-z$, Fig. 2; and Figs. 30 8 and 9 are sections showing a modified form of attachment of the auxiliary comb-plate to the comb-plate.

Similar letters of reference indicate corresponding parts.

A in the drawings represents the stationary comb-plate, B the reciprocating cutter-plate, C the stationary handle, D the oscillating handle, E the cap-plate, and F the auxiliary 40 comb-plate, of our improved hair-clipper to be used by barbers for cutting the hair close to the scalp. The cutter-plate B, like the comb-plate A, is provided with a series of teeth, as customary in hair-clippers of this class. 45 The comb-plate A is provided at its upper side with a longitudinal slot, a , into which is placed a detachable tongue, b , the ends of which are bent so as to engage the comb-plate and be prevented from shifting in the 50 groove a . The cutter-plate B is fitted by a corresponding longitudinal groove, a' , at its

under side onto the tongue b , and retained on the comb-plate by means of the cap-plate E, which is attached to the comb-plate by a threaded post, d , nut d' , and spring-washer d'' , as shown clearly in Figs. 2 and 4. The comb-plate A and cutter-plate B are hollowed out at their adjoining sides, so as to reduce the friction between the same. A handle, C, is attached by screws e to the comb-plate 60 and retained in stationary position thereon by the said screws A. Screw f retains the collar f' of the oscillating lever D, and engages a threaded socket, f'' , of the fixed handle, C, which socket forms the fulcrum on 65 which the lever D is oscillated by the alternating action of the hand on handles C D, and the action of a strong spiral spring, g , that is placed around the socket f'' and attached at one end to the handle D and at the other end 70 to a recess, g' , of the rear flange or rim, g'' , of the stationary handle C, as shown in Fig. 5.

The collar f' at the end of the oscillating lever D is provided with an arm, f^3 , having a toothed segment, f^4 , which segment meshes 75 with a rack, f^5 , at the rear edge of the cutter-plate B, so as to reciprocate the latter by the motion of the oscillating handle D.

The motion or stroke of the cutter-plate B is regulated by a suitable stop device, which 80 engages the rear edge of the cutter-plate B, and which is made in the form of a toothed segment, h' , that is pivoted to one of the guide-studs e of the fixed handle C, and arranged to mesh with the rack f^5 of the cutter-plate, said 85 segment abutting against stops h^2 of the comb-plate, so as to stop thereby the cutter-plate when it arrives at either end of its stroke.

In place of the oscillating segment h' , the stationary handle C may be provided with a 90 fixed lug, i , that projects into a recess, i' , of the cutter-plate B, as shown in Fig. 5; or any other stop device may be used, as we do not desire to confine ourselves to any special construction of the same.

The handles C and D are provided with the usual rests for the thumb and fingers for operating the clipper.

When it is desired to set the oscillating handle D to a greater or smaller angle toward the 100 stationary handles, the cap-plate S is removed by unscrewing the nut d' from the post d , after

which the cutter-plate B can be lifted and moved to one side or the other of the segment f⁴, whereby the oscillating lever D is set farther away from or closer to the stationary lever C. This forms an important feature in our improved hair-clipper, as it can thereby be readily adjusted to hands of larger and smaller size.

To the under side of the comb-plate A is applied an auxiliary detachable comb-plate, F, which is made of rubber or other suitable material, and attached to the comb-plate A by hollow spring-studs l', which are screwed into the body of the comb-plate and sprung into socket-holes l' of the auxiliary comb-plate, as shown in Figs. 8 and 9.

Several auxiliary comb-plates of different thicknesses are furnished with the hair-clipper and readily attached to or detached from the comb-plate, whereby it is possible to cut the hair in an even manner, either close to the skin or at any length from the same, while when a close cut is required the auxiliary plate is entirely removed and the clipper used without the same.

We are aware that hair-clipper having an auxiliary comb-plate that is removably secured to the stationary comb-plate, to increase the thickness of the stationary comb-plate of such hair-clipper, has been used heretofore, and we do not claim this broadly.

Having thus described our invention, we claim as new and desire to secure by Letters Patent—

35 1. The combination of a comb-plate having a longitudinal groove, a cutter-plate having also a longitudinal groove at the under side, an intermediate guide-tongue bent at both ends, a stationary handle attached to the comb-plate, an oscillating handle fulcrumed to the stationary handle and adapted to reciprocate

the cutter-plate, and a cap-plate attached to the comb-plate, substantially as set forth.

2. The combination of a stationary comb-plate having a longitudinal groove, a cutter-plate having a longitudinal bottom groove coinciding with the groove of the comb-plate, an intermediate guide-tongue having bent retaining ends, a stationary handle attached to the comb-plate, an oscillating handle fulcrumed to a socket of the stationary handle and provided with a toothed segment meshing with a rack at the rear edge of the cutter-plate, a cap-plate, and a screw-bolt and nut for attaching the cap-plate to the comb-plate, substantially as set forth.

3. The combination of a stationary comb-plate, a reciprocating cutter-plate having a rack at the rear edge, a stationary handle attached to the comb-plate and provided with a screw-socket, an oscillating handle pivoted to said socket, a screw for retaining the oscillating handle, a spiral spring acting upon said oscillating handle, an arm extending from the oscillating handle and having a toothed segment meshing with the rack of the cutter-plate, and a cap-plate attached by a screw-post and nut to the comb-plate, substantially as set forth.

4. In a hair-clipper, the combination of the stationary comb-plate having socket-holes with an auxiliary removable comb-plate having split spring clasps or studs for attaching it to the under side of the stationary comb-plate, substantially as set forth.

In testimony that we claim the foregoing as our invention we have signed our names in presence of two subscribing witnesses.

CHARLES REINHARDT.
HEINRICH LEBHERZ.
